CLAIM

The ornamental design for an implantable port, as shown and described.

DESCRIPTION

FIG. 1 is a perspective view of one embodiment of an implantable port showing our new design;

FIG. 2 is a top plan view of the implantable port of FIG. 1;

FIG. 3 is a bottom plan view of one embodiment of the implantable port of FIG. 1

FIG. 4 is a bottom plan view of an alternative embodiment of the implantable port of FIG. 1;

FIG. 5 is a left side elevation alive of the implantable port of FIG. 1;

FIG. 6 is a right side elevational view of the implantable port of FIG. 1;

FIG. 7 is a rear elevational view of the implantable port of FIG. 1;

FIG. 8 is a front elevational view of the implantable port of FIG. 1;

FIG. 9 is a perspective view of a second embodiment of an implantable port;

FIG. 10 is a top plan view of the implantable port of FIG. 9;

FIG. 11 is a bottom plan view of one embodiment of the implantable port of FIG. 9;

FIG. 12 is a bottom plan view of an alternative embodiment of the implantable port of FIG. 9;

FIG. 13 is a left side elevational view of the implantable port of FIG. 9;

FIG. 14 is a right side elevational view of the implantable port of FIG. 9;

FIG. 15 is a rear elevational view of the implantable port of FIG. 9; and,

FIG. 16 is a front elevational view of the implantable port of FIG. 9.

The broken lines shown throughout the figures are for illustrative purposes only and form no part of the claimed design.
